UNITED STATES PATENT OFFICE

JAMES T. STEWART, OF FOREST HILLS, NEW YORK, ASSIGNOR TO DUPLAN SILK CORPORATION, OF NEW YORK, N. Y., A CORPORATION OF DELAWARE

DESIGN FOR A TEXTILE FABRIC

Application filed June 16, 1930. Serial No. 36,066. Term of patent 3½ years.

To all whom it may concern:

Be it known that I, JAMES T. STEWART, a citizen of the United States, residing at No. 7531 Kessel Street, Forest Hills, county of Queens, State of New York, whose post-office address is 135 Madison Avenue, city, county, and State of New York, have invented a new, original, and ornamental Design for a Textile Fabric, of which the following is a specification, reference being had to the accompanying drawing, forming part thereof.

The figure is a plan view of a textile fabric showing my new design.

A single unit of my design is substantially comprised within the area defined by the indicating lines shown on the drawing, which unit is repeated over the surface of the fabric in the relation indicated.

I claim:

The ornamental design for a textile fabric substantially as shown and described.

JAMES T. STEWART.
